UNITED STATES PATENT OFFICE.

GARFIELD A. WOOD, OF DETROIT, MICHIGAN.

HYDRAULIC HOISTING DEVICE.

1,271,976.

Specification of Letters Patent. Patented July 9, 1918.

Original application filed January 15, 1917, Serial No. 142,406. Divided and this application filed June 6, 1917. Serial No. 173,091.

To all whom it may concern:

Be it known that I, GARFIELD A. WOOD, a citizen of the United States, and residing at Detroit, in the county of Wayne and State 5 of Michigan, have invented a new and Improved Hydraulic Hoisting Device, of which the following is a specification.

The present invention relates to hydraulic (oil) hoisting means whereby the front ends 10 of truck bodies are lifted for dumping purposes, and its object is to provide a construction which is cheaper than existing devices and one which is particularly suitable for light trucks, although not limited thereto. 15 It consists in a split clamping member extending around the cylinder at an intermediate point in the length thereof; in an improved head construction for the cylinder; in means connecting said clamping member 20 and said head construction for retaining the latter in place; in means whereby the cylinder and hollow piston rod which constitute the oil reservoir may be filled to a high level through a single port; and in various other 25 details of construction shown, described and claimed.

This application is a division of my former application Serial No. 142,406, filed January 15, 1917.

30 In the drawings, Figure 1 is a fragmentary side elevation, parts being broken away, showing one embodiment of the invention. Fig. 2 is a view corresponding thereto looking backwardly from a plane just behind the 35 vehicle seat. Fig. 3 is a fragmentary front view of the hoisting cylinder and support. Fig. 4 is a section on the line 4—4 of Fig. 3. Fig. 5 is a section on the line 5—5 of Fig. 4.

1 indicates the side bars, 2 the body pivoted to swing vertically about horizontal 40 pivots located near the rear end thereof, 3 the driver's seat, 4 the upright hoisting cylinder, the base 5 of which is supported from the side bars through the medium of a suitable cross frame preferably formed of angle-irons 6 to which the base is bolted. The upper end of the cylinder is braced from the outer ends of the front angle-iron 6 by means of tension rods 8 (having nuts 9 on each end 45 and suitable lock washers or the equivalent if desired) whose upper ends preferably pass through holes in the rear half 11 of a

clamping element that includes a front half 12 and the connecting bolts 13 and conforms to a circumferential groove 15 cut in the 55 outer surface of the cylinder.

The upper end of the cylinder receives a hollow head 16 which may have circumferential flanges 18 and 19 conforming to the inner surface of the cylinder and may be 60 machined out circumferentially to receive suitable packing 20 which, when the head is drawn downwardly as hereinafter described, allows a metal-to-metal contact between the head and the end surface of the cylinder and 65 seals the joint. A hollow piston rod 22, having a piston 23, slides up and down through the head and through a packing plate 24 that has an annular depending flange 25 arranged to project into and compress packing 26 in the upper inner portion of the head 16 to insure a tight joint between the latter and the piston rod. The packing plate is drawn down upon the head by means of the 70 nuts 27 on the bolts 28 and 29, spaced diametrically from each other, the former being threaded into a boss 30 on the member 11 and the latter into a boss 31 on an upward extension of the member 12.

Extending crosswise through the projecting end of the piston rod is a pivot bolt 33 upon which is supported an equalizing cross-bar 34 having pulleys 35 suspended from its outer ends. Cables 36, secured to the lower 75 ends of the depending body arms 38 of the 80 body 2, pass over the corresponding pulley and have their inner ends bent around the corresponding clamping bolt 13 and secured in place by suitable shackles 39.

Depending from the front cross-bar 6 is 85 an angle iron 40 upon one side of which is mounted a gear pump 41 (preferably that shown and claimed in my application for patent Serial Number 14479, filed March 15, 1915) that is driven from a longitudinally 90 extending shaft 42 of the vehicle in any suitable manner, for example, by the sprocket gears 43 and 44 (the latter being mounted on the opposite side of the member 40), the chain 45, the clutch pins 46 and the 95 clutch member 48 carried by the propeller shaft 42 of the vehicle. The clutch pins 46 are slidable longitudinally through the gear 100 shaft 42 through the medium of yoke arms 50 and

the actuating arm 51 rigid with the shaft 52 which is mounted in the lower ends of member 40 and a companion member 53. The specific construction described in this paragraph is claimed in my application for patent Serial Number 135,797, filed December 8th, 1916, and may be varied widely. In some instances the pump may be driven by a countershaft as shown in my application 10 for patent Serial Number 142,405, filed January 15th, 1917.

In the present instance, however, the link 55 to which the arm 51 is connected is pivoted at 56 to a hand lever 58 that is itself 15 pivotally supported at 59 on the front face of the member 12. Any suitable means is employed for limiting the throw of the hand lever in each direction. A similar connection, consisting of the hand lever 60 and link 61 constitutes an actuating means for 20 the valve arm 62 of the pump.

In order to allow the use of the interior of the cylinder above the piston as a reservoir for oil, the cylinder is provided with a 25 port 64 in the groove 15 opposite the member 12, and the latter is provided with a passage 65 with which the suction pipe 66 which leads to the pump is connected by a packing gland 68. A sealing washer 69 is 30 interposed between the member 12 and the cylinder. From the pump the oil is delivered through the pipe 70 and passage 71 (Fig. 4) to the space beneath the piston. The interior of the piston rod is also used as 35 a part of the reservoir, holes 72 (preferably cored out in the piston 23, thus avoiding any drilling of the piston rod 22) (Fig. 4) being provided to allow ingress and egress of the liquid. At its upper end the piston rod is 40 preferably closed by the diaphragm 73 and is perforated at 74 to admit air when the piston rod has risen a short distance whereby a tight seal is secured and the partial vacuum which would otherwise obtain in the 45 rod is broken in the general manner shown and claimed in my application for patent Serial Number 14480, filed March 15, 1915. The upper end of the piston rod might in some cases be left open as the cross-bar 34 50 would exclude foreign objects, but the tendency for the oil to slop over as the piston sinks would be objectionable.

Considering those features of cylinder and piston rod construction thus far described, it will be seen that it would not be possible to fill that portion of the cylinder 55 above the single port 64 by pouring liquid through said port. It would also be objectionable to pierce the cylinder at a higher level, and the head 16 and packing plate 24 could not well be pierced to allow the escape of the trapped air. In order to avoid these 60 objections and at the same time provide a cheaper construction, the piston rod is 65 pierced at a point located above the upper

edge of the piston a distance less than the distance from the port 64 to the lower surface of the head 16 as indicated at 76. The cylinder and piston rod being filled in an obvious manner to the level of the upper 70 edge of the port, it is then only necessary to work the pump to elevate the piston until it reaches the lower edge of the port 64, remove the plug 78 for an upward extension 79 of the passage 65 in the member 12 and 75 pour in additional oil to cover the port to a depth sufficient to prevent air from being drawn into the suction pipe 66, in which operation the air will escape through the passage 76 (which would then be just below 80 the head 16), the interior of the piston rod, and the passage 74 and allow the oil to rise as high as the entrance to the passage 79 if desired.

From the foregoing it will be understood 85 that liquid may be either drawn from the reservoir through the suction pipe 66 and discharged through the pipe 70 for lifting purposes, or may be by-passed from the pipe 70 to the pipe 66 for lowering, or may be 90 circulated continuously within the pump casing, as described in my application Serial Number 14479, referred to above. It will also be seen that the upward movement of the piston rod is automatically limited when 95 the piston uncovers the port 64.

The details of construction may be varied within wide limits without departing from the spirit of the invention, and I do not, therefore, wish to be limited except as indicated by the subjoined claims. 100

I claim:—

1. An upright hoisting cylinder, clamping means encircling the upper portion of said cylinder in a groove, a piston and piston 105 rod slideable in said cylinder, an annular head for said cylinder, and bolts associated with the clamping means whereby said head is retained in position.

2. An upright hoisting cylinder, clamping means encircling the upper portion of said cylinder in a groove, a piston and piston rod slideable in said cylinder, an annular head for said cylinder, the inner face of said head being grooved to receive packing for 110 sealing the joint between it and the piston rod, a packing plate arranged to engage and compress said packing, and bolts associated with said clamping means whereby said packing plate is caused to draw the 115 head down onto the cylinder.

3. An upright hoisting cylinder, a piston and piston rod slideable therein, a head for the cylinder, a port in the cylinder some distance below the head, the lower end of the piston rod being in communication with the space between the piston rod and the cylinder, a passage externally of the cylinder extending from said port to a higher level, said piston rod being perforated at a point 120

considerably above the piston whereby when liquid is introduced through the passage, the air above the port and between the piston rod and the cylinder may escape through 5 the piston rod.

4. An upright hoisting cylinder, a hollow piston and piston rod slidable therein, a head for the cylinder, a port in the cylinder some distance below the head, the lower end 10 of the piston rod being in communication with the space between the piston rod and the cylinder, a passage externally of the cylinder extending from said port to a higher level, said piston rod being perforated at a point located above the piston a 15 distance less than the distance from the port to the head whereby, when liquid is introduced through the passage, the air above the port and between the piston rod and the cylinder may escape through the piston rod.

5. An upright cylinder, an annular head for the upper end of the cylinder, a piston slidable in the cylinder, a hollow piston rod connected to the piston and projecting 25 through the head in sealed relation thereto, the piston rod, when in lowered position, being in communication with the space between it and the cylinder at three different levels, one just below the head, a second near the 30 lower end of the rod, and the third some distance above the second, the cylinder having a port located below the lower surface of the head a distance at least equal to the difference in level between the second and third 35 points of communication between the interior of the piston rod and the space between the rod and the cylinder.

6. An upright hoisting cylinder having a groove therein near its upper end and being 40 perforated at the groove, a piston and piston rod reciprocable in the cylinder, a divided clamping element extending around the cylinder and having a portion thereof received in the groove and around the perforation therein, whereby when the parts of 45 the element are drawn together by a movement transversely of the cylinder a close joint is secured between the element and the adjacent surface of the groove, the clamping element having a passage in registration 50 with the perforation in the groove, the space between the cylinder and piston rod serving as a reservoir for liquid, and means for withdrawing the liquid through the passage and expelling it below the piston to cause the latter to rise.

7. An upright cylinder, a head for the upper end of the cylinder, a piston slidable in the cylinder, a piston rod connected to 55 the piston, the piston rod being hollow and projecting through the head, means for sealing the joint between the piston rod and the head, automatic means for limiting the upward stroke of the piston, the interior of 65 the piston rod being in communication with

the annular space surrounding the rod at two different levels spaced considerably apart near the lower end of the piston rod, both of said levels being below the head when the piston rod is at the upper limit 70 of its movement.

8. A cylinder having a port in its wall near one end, a piston and piston rod slid- 75 able in said cylinder, a clamping element conforming to the cylinder around the port, means for drawing the clamping element transversely of the cylinder into sealed relation therewith, said element having a passage therein in communication with the port through which liquid in the cylinder 80 is allowed to escape.

9. An upright hoisting cylinder having a port in its wall near its upper end, a piston and piston rod slidable in the cylinder, a divided clamp extending around the cylinder at the port, one of the divisions of the clamp covering the port, means for sealing the joint between said division and the port, 85 said division having formed therein an upwardly extending passage through which liquid may be poured into the cylinder 90 through the port.

10. An upright hoisting cylinder having a port in its wall near its upper end, a pis- 95 ton and piston rod slidable in the cylinder, a divided clamp extending around the cylinder at the port, one of the divisions of the clamp covering the port, means for sealing the joint between said division and the port, 100 said division having a passage leading from the port, and a downwardly extending pipe communication with the passage.

11. An upright hoisting cylinder having a port in its wall near its upper end, a piston and piston rod slidable in the cylinder, an annular head for the upper end of the cylinder, a clamp passing around the cylinder at the port, said clamp having an upward extension at one side and said extension having a passage leading to the 110 port, a short bolt connecting the head to the extension and a longer bolt connecting the head and the clamp at a point spaced angularly about the axis of the cylinder 115 from the short bolt.

12. An upright cylinder, including an annular upper head, a piston and hollow pis- 120 ton rod reciprocable in the cylinder, said piston rod passing through the upper head and forming therewith a sealed joint, the interior of the piston rod being in communication with the annular space surrounding the rod at a point near the lower end of said rod, a port in the cylinder wall con- 125 siderably below the head, means in sealing relation to the cylinder around the port and extending upwardly therefrom for forming an upwardly opening passage through which liquid may be poured into the cylinder, said passage communicating with the 130

interior of the cylinder at the port only and terminating somewhat below the upper end of the piston rod.

13. In combination, an upright cylinder, 5 a lower end for the cylinder, a piston and piston rod slideable in the cylinder, a pump for forcing liquid between the piston and said lower end, the space between the cylinder and the rod above the piston constituting a storage chamber for liquid, means 10 for limiting the upward movement of the piston, said means including a port in the wall of the cylinder near the upper end, a suction pipe leading to the pump, and a 15 divided clamp including a hollow portion conforming to the cylinder and surrounding the port and in communication with the upper end of the suction pipe, said clamp including another portion on the opposite side of the cylinder, and means for drawing the two portions toward each other transversely of the cylinder.

14. An upright cylinder, a piston and hollow piston rod reciprocable therein, the 25 piston rod projecting from the upper end of the cylinder and having its interior in communication with the annular space surrounding said rod at substantially the lower end thereof, means for forming a passage 30 opening into the cylinder near the upper end thereof, said passage connecting with

the lower end of the cylinder below the piston and also extending considerably above the first mentioned opening into the cylinder, but terminating below the upper 35 end of the piston rod, a removable plug for the upper end of said passage, said passage communicating with the cylinder only at the two points mentioned.

15. An upright cylinder, a piston and 40 hollow piston rod reciprocable therein, said rod projecting from and in sealed relation to the upper end of the cylinder, a closure for the upper end of the rod, the interior of the rod being in communication with the 45 annular space between it and the cylinder at substantially the lower end of the rod, a vent for the upper end of the rod whereby the interior of the rod is in communication with the atmosphere at least throughout 50 the greater portion of the movement of the rod, means for forming a passage opening into the cylinder at substantially two levels only, one being below the piston and the other being at a point near the upper end of 5. said cylinder, said passage opening upwardly above the point at which it communicates with the upper portion of the cylinder and having a plugged entrance below the closure for the upper end of the piston 6 rod.

GARFIELD A. WOOD.
